Herbert W. Day,
by Elmer Booth, Jameson and Jameson Hitlys.

UNITED STATES PATENT OFFICE.

LEE H. PARKER, OF BOSTON, AND HERBERT W. DAY, OF WOLLASTON, MASSACHUSETTS, ASSIGNORS TO SPRAY ENGINEERING COMPANY, OF BOSTON, MASSACHUSETTS, A CORPORATION OF MASSACHUSETTS.

APPARATUS FOR APPLYING COATING.

Original application filed October 9, 1920, Serial No. 415,737. Divided and this application filed March 1, 1922. Serial No. 540,116.

To all whom it may concern:

Be it known that we, LEE H. PARKER and HERBERT W. DAY, citizens of the United States, and residents, respectively, of Boston and Wollaston, in the counties, respectively, of Suffolk and Norfolk, State of Massachusetts, have invented an Improvement in Apparatus for Applying Coating, of which the following description, in connection with the accompanying drawings, is a specification, like characters on the drawings representing like parts:

This application is a division of our co-pending application Serial No. 415,737, filed October 9, 1920, now Patent No. 1,425,833.

This invention relates to apparatus for applying coating and which while it may be of general application and applicable to coating applying devices, apparatus and methods of various types, is in the disclosed embodiment an improvement upon the invention disclosed in the patent to Herbert W. Day, No. 1,321,014, dated November 4, 1919.

The coating, if a liquid, may be a paint, japan, varnish or other suitable coating medium, or it may if desired be a solid in powdered form, and the material or surface to which it is to be applied may be of any character such for example as wood, metal or other material.

An important object of our invention is to provide an industrial tool or appliance and to perfect a method whereby paint or other coating material may be projected onto a surface, and even at some considerable distance from the user of the tool or appliance, without any scattering of the coating material beyond those parts of the surface that are intended to be coated. Other objects of the invention will be set forth hereinafter.

Referring more particularly to the drawings wherein we have represented certain embodiments of our invention:—

Fig. 1 is a vertical longitudinal section of a tool constructed in accordance with our invention;

Fig. 2 is an end elevation of the structure shown in Fig. 1; and

Fig. 3 is a view, partly in side elevation and partly in vertical section, of the dis-

charge end of a coating tool and showing a further embodiment of the invention.

We shall proceed to describe our invention as applied to a paint gun or coating appliance like that shown in the said patent to Day, but it is distinctly to be understood that our invention is in no wise limited in its application to such type of gun or appliance, but that it may be employed upon guns or appliances of various other types. The ensuing description therefore of one type of gun or appliance to which the invention is applied is in no sense a limitation upon the scope of our invention.

The tool or appliance may be of any suitable material, but is preferably metallic and may be of the general form shown in the patent to Day, No. 1,172,233, dated February 15, 1916, or of any other suitable form or construction. The body 1 is preferably provided with a handle or extension 2 integral therewith and provided with a guard 3 enclosing the free end of the valve operating lever 4 pivoted at 5 upon the body 1. The said operating lever 4 is represented as of general trigger form.

The handle 2 is provided with a passage 6 for the paint or other suitable coating liquid or powder which may be supplied through gravity or under pressure if desired and also with a passage 7 for the air or other suitable fluid under pressure. In the form of tool herein shown we have represented the passages 6, 7, as pipes suitably secured in the body 1 and as communicating at their inner ends with passages 8, 9 cored or otherwise suitably provided in the body 1. Controlling the paint supply passage 8 is a valve which may be of any suitable form, but which is herein represented as an axially movable piston or plunger 10 positioned within a valve casing 11 and having a stem 12 extending through the valve casing into contact with the operating lever 4, as clearly shown in Fig. 1. The valve here shown as a piston or plunger is normally held seated by a coiled spring 13 surrounding the stem 12 and seated in a recess 14 in a cap 15 threaded at 16 into the body 1 which is similarly threaded at 17.

The passage 9 for the air is controlled by a similar valve not herein shown, but pref-

erably the same as the corresponding valve 18 shown in Fig. 2 of the patent to Herbert W. Day, No. 1,368,612, dated February 15, 1921, the spindle of such valve contacting 5 with the valve operating lever preferably so shaped as to engage both valves.

The body 1 is cored to provide a longitudinal passage 20 which is internally threaded at 21, 22 for the reception respectively of a tubular member 23 threaded at 24 and a needle valve 25 threaded at 26. The tubular member 23 at its forward end is preferably suitably formed to permit the passage of the coating material issuing 15 from the valve chamber 10 into the passage 27 and thence into the circumferential space 28. For this purpose the forward end of the tubular member is preferably square at 29. Thus the coating material 20 when the valve 10 is opened is permitted to flow through the passage 6, the valve casting 11, the passages 27, 28, and thence past the square formation 29. Upon the forward end of the tubular member 20 is 25 threaded or otherwise positioned a cap 30, which may if desired be similar to the corresponding member in the said Day Patent No. 1,172,233. The needle valve 25 is seated at the outer end in the cap 30 as 30 indicated in Fig. 1, and the forward end of the said needle valve is guided and positioned by any suitable means, as for example by a coiled wire 31 encircling the head of the valve and maintaining it in a 35 central position when the valve is unseated. The rear end of the valve 25 may be provided with a suitable lock nut 32.

The air passage 9 is in communication with a passage 33 indicated in dotted lines 40 in Fig. 1, and which is itself in communication with the valve chamber containing the valve 18. Extending from such valve chamber is an air passage 34 indicated in dotted lines in Fig. 1 and communicating 45 with a passage 35 forming an enlargement of a passage 36 of the tubular member 20. When the valve casing is opened, the air flows through the passage 33, past the valve 19, through the passages 34, 35, and into 50 the passage 36 governed or controlled by the needle valve 25.

Upon the outer end of the body 1 is threaded or otherwise suitably secured a preferably cap-like member 37 herein 55 shown as having a concaved or curved inner surface 38 and a small central opening 39 in line with the axis of the needle valve 25. The length of the threaded portion 40 of the cap like member 37 is sufficient to 60 permit adjustment of the member 37, so as to provide for the effective formation of a film and the variation of the thickness thereof as described in the said Day Patent No. 1,172,233. Such film is constantly 65 formed and maintained by capillary ac-

tion between the surface 38 and the outer surface 41 of the inner cap 30, which are brought close enough together to insure such action. The air entering through the passage 36 breaks through the film at the 70 central part of the cap and discharges the same upon the work in very fine globules. Said film is constantly broken by the air or other fluid, but is constantly restored through the action of capillarity. Hence 75 the coating material may be merely under suction due to capillary action. The maintenance of the supply of coating material is not dependent upon the presence of the air pressure which is used merely to break 80 the film and discharge the globules. We effect through the described construction a very fine division of the coating material 85 as set forth in the said Day Patent No. 1,172,233. 90

While we have described at some length means whereby a film of coating material is formed, disrupted and discharged, we desire it to be understood that our invention is not limited in its application to the 95 formation of a film, since the coating material may be brought or supplied to the point of ultimate discharge in any suitable manner, whether as a film formation or otherwise, or as shown for example in the 100 patent to Burdick, No. 649,430, dated May 15, 1900, and in the patent to De Vilbiss and Mueller, No. 1,260,522, dated March 26, 1918.

The construction of parts thus far described effects the formation of a mass of 105 spray of general conical form issuing through the orifice 39, but generally circular in cross-section. This result is effected by the disrupting of the film formed 110 between the cap-like members 30, 37, through the agency of the air or other suitable fluid in the manner already described.

As disclosed in the said Day Patent, No. 1,321,014, means have heretofore been provided for discharging supplemental jets of air upon the discharged spray for the purpose of changing the shape of the discharged spray from circular form into that of a relatively thin sheet, the disclosure in 115 the said Day Patent No. 1,321,014 being of means whereby the mass of spray as discharged is given any form between that of a relatively thin sheet and a cone or mass circular in cross section.

Our invention constitutes an advance and 120 an improvement upon those tools or appliances having means for discharging supplemental jets of air upon the discharged coating material, and as previously stated is not limited in its application to those types of tools or appliances wherein a film formation is created or established. We will, however, disclose the essential features of our invention as applied to a tool 125 130

or appliance wherein such film formation is created.

In the use of the tool of our invention we are enabled to break up the coating material into globules or particles of any desired fineness. The paint or other coating material is broken up by the air issuing past the needle valve 25 to a certain degree of fineness, but it is frequently desirable to break up the coating material to greater degrees of fineness. By providing supplemental air jets under full force or pressure, the coating material is broken into particles or globules of the most extreme fineness. By modulating or varying the pressure of the supplemental air jets any desired intermediate degree of fineness of the coating particles is secured.

In the disclosed embodiment of the invention we provide a generally cylindrical conical member 42 having any suitable number, and herein two, tubular extensions or passages 43, 44, preferably diametrically opposed to each other and having discharge passages 45, 46, which as shown most clearly in Fig. 2, are of substantial length transversely of said tubular passages 43, 44, and are desirably inclined toward each other as clearly represented in Fig. 1. Said discharge passages are formed as slots which may slope at any desired angle so that the supplemental sheets of discharged air may meet as at the point A in Fig. 1, or at a point considerably in advance thereof. In either case, the supplemental air sheets act upon the coating material and air which are discharged through the passage 39 so as further to break up the same and also to provide a protective sheathing, wall or the like. In addition we provide for the discharge of other supplemental air jets through small passages desirably circular in contour. Such passages, openings or perforations, may be at any desired points as for example at the points 45^a, 46^a in Fig. 1. This permits the discharge of supplies of supplemental air upon the coating material already discharged through the passage 39 and thereby effects a further breaking up of the material. The air discharged through the slots 45^a, 46^a effects still further comminution of the discharged material and the air discharged through the openings 45, 46 provides for the protective sheathing, coating or wall.

In certain forms of our invention the perforations 45^a, 46^a for the supplemental air jets may be formed in or as an enlargement of the central or some other part of the slots 45, 46.

The two supplemental air passages 43, 44 with their terminal openings 45, 46, 45^a, 46^a, are respectively in constant communication at their inner ends through passages 47, 48 with an annular passage or groove 49 shown as formed in the outer surface of the for-

ward end of the body 1 and communicating through the longitudinally extending passage 49' with a passage 50 in the body member 1 and which is in communication with the main air passage 35 through a small port 51.

This port is controlled by a valve 52 threaded into an opening 53 of the body 1 and having a preferably knurled head 54 by which it may be turned manually. The inner tapered head 55 of said valve is adapted to be seated so as to close the port 51 or to be opened fully or to any desired extent, thus regulating the air supply through the said passage 50. The valve 52 constitutes a reducing valve whereby the supplemental air pressure can be regulated if desired and whereby any desired degree of fineness of the discharged coating material may be obtained. Obviously the annular groove 49 may be formed in the inner surface of the member 42.

In order effectively to seat and control the position of the cylindrical member 42, the body 1 is herein shown as provided with a spherical surface 56 upon which is received the correspondingly shaped inner surface 57 of the cylindrical member 42. Co-operating with the said spherical seat is the guiding surface 58 of the cap-like member 37.

With said guiding surface 58 there contact the projections 59, 60, which extend from the walls of the supplemental air supply passages 43, 44. This construction may be varied as desired.

Cooperating to hold the cylindrical member 42 in position, there is desirably provided a coiled spring 61 between the inner end of the cap-like member 37 and the cylindrical member 42.

While in the disclosed embodiment of the invention the supplemental air passages 47, 48 are represented as in constant communication with the annular groove or passage 49, whatever be the circumferential position of the cylindrical member 42, our invention obviously is not limited to such feature of constant communication, although this is desirable. In other types of tools or appliances to which our invention may be applied, the supplemental air passage or passages may not be in constant communication with the source of compressed air supply.

However, in the disclosed type or embodiment of our invention the discharge of the supplemental air jets is not interrupted or cut off by movement of the cylindrical member 42, but through the manipulation of the valve 52. Our invention, however, is not limited in this respect.

In the said Day Patent 1,321,014 the supplemental jets of air are discharged through orifices which are inwardly directed or in-

clined toward the axis of the tool or appliance, or rather toward an outward prolongation of the said axis. In such other types of coating tools as we are familiar with, 5 the supplemental air jets are discharged at an inward inclination so as to intersect, if but very little extended, a prolongation of the axis of the tool. The general result of such construction is to transform the dis- 10 charged coating material from a mass circular in cross-section into the form of a relatively thin sheet, though as already stated, in the case of said Day Patent 1,321,014 any form between that of a circle and a relatively 15 thin sheet may be secured.

In all said cases, however, the supplemental air jets are discharged directly onto the discharged coating material at a point close to the point of ultimate discharge of 20 the coating material from the tool. In none of said cases has any attempt been made to create by the supplemental air jets protective sheathings or air walls that substantially encompass or partially surround the 25 discharged coating material which has been reduced to a sheet-like condition.

In accordance with the scope and purpose of our invention we provide for a discharge of the supplemental air jet or jets in such a 30 way and with such a result that the said jets themselves become or are more or less flattened out or transformed into layers of air, and which position themselves at the opposite faces of the discharged coating material. 35 Thus the supplemental air jets perform several important results. They serve first to flatten the discharge or spray of coating material into a general sheet-like form and since they themselves are more or less flattened in 40 accordance with our invention, they secondly constitute a protecting sheathing or envelope or an air wall or walls which effectively prevent the outlying or smaller particles of the coating material from disseminating or flying onto any part of the surface that is not desired to be coated. On the contrary, all the outlying particles are guided and directed in such a way that all 45 the discharged coating material is received upon the surface in a relatively thin line. The result is that the user of the tool or appliance may stand at a considerable distance from a wall or other surface that is to be coated and may project the coating material 50 in the described relatively thin line upon the exact parts of the surface desired without overlapping onto adjacent parts of the surface or onto other surfaces.

The means of our invention may be embodied in various types or forms of tools.

Preferably, however, we carry out our invention in substantially the following manner.

The supplemental air jets themselves are 55 so discharged as to provide for and secure

the desired result. The invention herein disclosed therefore differs specifically from that disclosed in our co-pending application Serial No. 415,737, wherein we have described certain prolongations, abutments, or 70 mechanical parts for securing the desired result.

Within the scope of our invention prolongations or abutments may be positioned 75 at any suitable point and may receive the impact of the supplemental air jets in any suitable manner. In Fig. 3 we have represented the abutments, other forms of which are shown in our said co-pending application Serial No. 415,737, as located within the points of discharge of the supplemental air jets. In said Fig. 3, we have represented the supplemental air passages 62, 63 as prolonged as indicated at 64, 65, 80 though within the scope of our invention they may be of any desired length. Desirably the prolongations 64, 65 are made as separate nipples threaded internally as indicated at 66, 67, and received upon externally threaded parts 68, 69 of the passages 62, 63. At their forward extremities the said nipples 64, 65 are provided with discharge 85 passages 70, 71, which may be formed as small perforations or otherwise, and between said discharge passages and the point 72 of the discharge of coating material, we provide abutments 73, 74, which desirably are rounded substantially as shown. The said abutments 73, 74 are so located and are so shaped as to be stream lined, whereby the 90 supplemental air discharge from the openings 70, 71 tends to follow the contour of said abutments, and thus being directly inwardly toward each other will strike the discharged coating material, reducing the same to more or less of a line, and at the same time will form themselves into a protecting 95 wall or tubing for the coating material produced. In the use of a paint gun such as herein disclosed, there is created somewhat 100 of a vacuum adjacent to the point of discharge of the coating material, and the result of this is to cause the supplemental air jet to hug or keep in contact so long as possible with the abutment 73, 74.

Having thus described one illustrative embodiment of my invention, I desire it to be understood that although specific terms are employed they are used in a generic and descriptive sense and not for 110 purposes of limitation, the scope of the invention being set forth in the following claims.

Claims:

1. Means for applying coating comprising 125 means to supply coating material, means to subject the same to the action of compressed air, thereby effecting the discharge of the coating material, means to discharge compressed air supplementally upon the dis- 130

charged coating material at opposite sides of the discharge of coating material, thereby reducing said discharge of coating material to sheet form flaring from the point of discharge therefrom and unconfined at its edges, and means to discharge other supplemental jets onto the supplementally discharged air so that the latter is itself reduced to sheet form flaring from its points 10 of discharge.

2. Means for applying coating comprising means to supply coating material, means to subject the same to the action of compressed air, thereby effecting the discharge of the 15 coating material, means to discharge compressed air supplementally upon the discharged coating material at opposite sides of the discharge of coating material, thereby reducing said discharge of coating material 20 to sheet form flaring from the point of discharge therefrom and unconfined at its edges, and means to discharge other supplemental jets onto the said supplementally discharged air so that the latter is itself reduced to sheet 25 form.

3. Means for applying coating comprising means to supply coating material, means to subject the same to the action of compressed air, thereby effecting the discharge of the 30 coating material, means to discharge compressed air supplementally upon the discharged coating material at opposite sides of the discharge of coating material, thereby reducing said discharge of coating material 35 to sheet form flaring from the point of discharge therefrom and unconfined at its edges, and means to discharge other supplemental jets of air onto the said supplementally discharged air, so that the latter 40 is itself reduced to sheet form flaring from its points of discharge and unconfined at the edges thereof, so as to constitute substantially coincidentally flaring air-wall sheets for the said flaring sheet of discharged coating material.

4. Means for applying coating comprising means to supply coating material, means to subject the same to the action of compressed air, thereby effecting the discharge of the 50 coating material, means to discharge com-

pressed air supplementally upon the discharged coating material at opposite sides of the discharge of coating material, thereby reducing said discharge of coating material to sheet form flaring from the point of discharge therefrom and unconfined at its edges, and means to discharge other supplemental jets onto the said supplementally discharged air in general superposition upon the said supplementally discharged air. 55 60

5. Means for applying coating comprising means to supply coating material, means to subject the same to the action of compressed air or other motive agent, thereby effecting the discharge of the coating material and 65 means to discharge compressed air or other motive agent at opposite sides of the discharge of coated material and in a plurality of jets at each of said opposite sides.

6. Means for applying coating comprising means to supply coating material, means to subject the same to the action of compressed air or other motive agent, thereby effecting the discharge of the coating material and means to discharge compressed air or other 70 motive agent at opposite sides of the discharge of coated material and in a plurality of jets at each of said opposite sides and in general superposition at each of said opposite sides. 75 80

7. Means for applying coating comprising means to supply coating material, means to subject the same to the action of a motive agent, thereby effecting the discharge of the coating material in a mass generally circular in cross section, means to discharge a motive agent supplementally upon the discharged mass, thereby to reduce it to sheet form, and means at opposite sides of the point of discharge of the coating material 85 but between the same and the points of discharge of the motive agent supplementally, to cause such supplementally discharged motive agent to assume the form and position of a sheet like protective cover for the discharged mass of coating material. 90 95

In testimony whereof, we have signed our names to this specification.

LEE H. PARKER.
HERBERT W. DAY.
